UNITED STATES PATENT OFFICE.

CYRUS K. VILAS, OF ALSTEAD, NEW HAMPSHIRE.

FIRE-BOX.

SPECIFICATION forming part of Letters Patent No. 261,105, dated July 11, 1882.

Application filed April 18, 1882. (No model.)

To all whom it may concern:

Be it known that I, CYRUS K. VILAS, of Al-
stead, in the county of Cheshire and State of
New Hampshire, have invented a new and Im-
proved Fire-Box, of which the following is a
full, clear, and exact description.

The object of my invention is to provide a
new and improved fire-box for stoves and heaters
from which the ashes and clinkers can be
removed very conveniently.

This invention relates to an improvement in
fire-boxes of that class adapted to revolve and
to be used either end downward or as a grate;
and it consists of a spherical or globe-shaped
chamber or box provided with apertured or
slotted covers covering opposite openings there-
in, combined with a stove or heater having an
opening in its bottom provided with beveled
edges, substantially as hereinafter more fully
set forth and claimed.

Reference is to be had to the accompanying
drawings, forming a part of this specification,
in which similar letters of reference indicate
corresponding parts in both the figures.

Figure 1 is a cross-sectional elevation of a
stove provided with my improved fire-box.
Fig. 2 is a plan view of the fire-box, showing it
detached from the stove.

The fire-box A is made of cast metal or other
suitable material, and in the shape of a globe
or any other suitable shape, and is provided
with two opposite apertures, which are closed
by pivoted lids B, which are curved to form a
part of the fire-box when they rest over the
openings. The lids are provided with numer-
ous apertures, C, or slots, so that they can
serve as grates. The lids are each pivoted to
the fire-box at one of their ends, and at the
other ends are provided with a handle-stud, D,
and can be locked in position on the fire-box
by means of spring-latches E, of any suitable
construction. The lids are preferably pivoted
to move sidewise, but can be pivoted or at-
tached to the fire-box in any other suitable
manner. The fire-box is provided with two
opposite projecting pivots, F, journaled in the
sides within the stove or heater G, one of which

pivots has a squared end to receive a key for
rotating the fire-box. The bottom H of the
stove or heater G is provided with a circular 50
aperture, J, provided with beveled edges H',
against which the covers or lids can fit so
closely that all the draft must pass through
the fire-box, and cannot pass around the fire-
box or covers. The fire-box may be made larger 55
or smaller, as may be desired.

The operation is as follows: One of the lids
B is opened and wood and coals are placed
in the fire-box, and are then ignited, the draft
passing through into the fire-box through the 60
apertures of the lower lid B and escaping
through the other lid. If the ashes are to be
removed, the fire-box is rocked by swinging the
same to and fro by means of a key on pivot F,
provided with a squared end. Then the globe 65
or fire-box is inverted, so that the bottom lid
B will be at the top. If this lid is opened, the
cinders and clinkers can be removed and fresh
coals placed in the fire-box. The fire-box may
remain in this position until a fresh quantity 70
of coals is again required. It will not always
be necessary to shake the fire-box to remove
the ashes, for by overturning the fire-box the
coals, cinders, and ashes in the same will be
shaken so thoroughly that the ashes will drop 75
through the apertures of the bottom grate-
cover. If the fire-box must be adjusted higher
or lower to fit closely in the openings J, wash-
ers can be placed under the pivots F to raise
the same, or the washers can be removed, as 80
the case may be; or it may be raised or lowered
in any other convenient manner.

Having thus described my invention, I claim
as new and desire to secure by Letters Patent—

The combination, with the spherical or globe-
shaped fire box or chamber, adapted to re-
volve, and having the slotted or apertured cov-
ers, of the stove or heater provided in its bot-
tom with an opening having the upper bev-
eled edge, substantially as herein set forth. 85

CYRUS K. VILAS.
